GOLF TEE CONTAINER

Claude E. Hand III, 5325 Donald St.,
Eugene, Oreg. 97405

Filed Oct. 24, 1972, Ser. No. 299,826

Term of patent 14 years

Int. Cl. D21—02

U.S. Cl. D34—5 GT

FIG. 1 is a side elevational view of the golf tee container,

FIG. 2 is a front elevational view of the container of FIG. 1,

FIG. 3 is a rear elevational view of the golf tee container,

FIG. 4 is a top plan view of the golf tee container shown in FIG. 1, and

FIG. 5 is a bottom plan view of the golf tee container shown in FIG. 1.

I claim:

The ornamental design for a golf tee container, as shown.
